BOWLING PIN

Edgar B. Nichols, 325 W. Main St., Moorestown, N.J.
Filed May 14, 1962, Ser. No. 194,250
7 Claims. (Cl. 273—82)

This application relates to bowling pins, and has for its object to provide bowling pins which are of uniform size and weight, notwithstanding variations in the specific gravity of the wood of which the pins are made.

A further object of the invention is to provide a bowling pin which is made of several pieces of wood, which is cheaper to manufacture than the standard one-piece pin, but which will nevertheless withstand the wear and tear of usage without significant damage for a much longer period than the standard one-piece pin.

In the accompanying drawings, I have shown two forms of my improved pin and also certain steps in its process of manufacture, and in the said drawings:

FIG. 1 is a vertical section of my improved pin;

FIG. 2 is a transverse section on line 2—2 of FIG. 1;

FIG. 3 is a perspective view showing the several pieces out of which the pin is made; and

FIG. 4 is a side elevation, partly in section, showing a modification of the pin shown in FIG. 1.

As shown in FIG. 3, the pin is made from four blocks 1 of rectangular cross-section and two center core pieces 2 and 3 of square cross-section. The four blocks 1 are of a length slightly greater than the height of the pin and are twice as wide as they are thick. The blocks are cut from the log so that the grain is diagonal with respect to the side faces of the blocks as indicated by the lines 4 in FIG. 2.

The core piece 2 is slightly longer than the core piece 3 and these two pieces should be of exactly the same cross-section so the cores are preferably made of one piece of the same length as the blocks and sawed into two separate pieces of the relative lengths shown. All the pieces, both core and blocks, should have smoothly finished outer faces. Also, the corner angles should be exact right angles but it is not necessary that the dimensions of the blocks or the core be exact to closer tolerances than can be obtained with ordinary wood-working machines.

In making the pin the four blocks and the two core sections are weighed and as the weight of the finished pin is a known fraction of the combined weight of the separate pieces, it can be determined how much greater than the required minimum the weight of the pin will be.

To reduce the weight of the pin to the required minimum, a hole 5 is bored axially of the core piece 3 to the depth required, as indicated by a table showing the depth of hole needed for each unit of overweight. After the piece 3 is bored to the proper depth, the six pieces are glued together in the arrangement shown to form a billet of the same size and shape as the solid wooden blocks from which the standard bowling pins are made. The fabricated pieces are processed in the same manner as the solid blocks to produce the finished pin.

My improved fabricated pin will withstand the impacts of usage without damage for a much longer period than pins made from a single block of wood wherein the grain runs in the same direction throughout the area of the block. In pins made from such blocks the angle of the grain of the wood to the surface of the pin varies from substantially parallel to substantially perpendicular. The sides of the pin where the grain of the wood is more nearly parallel to the surface are damaged much more frequently by the impact of the balls than portions of the circumference where the grain is more nearly perpendicular to the surface. When the pin is made of four sections, the blocks can be cut so that the grain at

the middle of the ninety degree section is perpendicular to the surface and hence the grain at no portion of the surface is at an angle of less than 45 degrees to the surface.

One of the advantages of my improved pin is that variations in the thickness and width of the several blocks do not affect the strength of the glued joint or in any way affect the procedure of making pins of uniform size and weight. In assembling the blocks to make the billet, glue is applied to two opposite faces of the aligned blocks 1. Two of the blocks 1 are then placed in position against the glued surfaces of the blocks with one edge of each block 1 aligned with one of the unglued surfaces, respectively, of the blocks 2. Pressure is then applied to the exposed faces of the blocks 1 along the side adjacent the blocks 2 and maintained until the glue is set. Glue is then applied to one edge and one side of each of the two remaining blocks 1 and these blocks are assembled with the Z-shaped assembly resulting from the first operation. Pressure is then applied to the exposed longitudinal corners of the two added blocks 1 and maintained until the glue is set. By this method of assembly, strong glued seams will be obtained regardless of variations in the dimensions of the several blocks.

My improved fabricated pin is particularly useful when used in conjunction with the nylon band and coating disclosed in my pending application Serial No. 608,036, filed September 5, 1956, and in FIG. 4 I have shown a pin so constructed. As here shown, the pin formed as above described and shown in FIG. 1, is provided with a wide shallow groove 10 around its mid-portion and a molded nylon band 11 is sealed in the groove. As described in said application, the bottom of the groove is longitudinally convex when cut and then flattened to a cylindrical contour by hammering. The shoulder 12 at the upper edge of the groove is somewhat higher than the shoulder 13 at the lower edge of the groove and the band 11 is applied by heating the band sufficiently for it to stretch over the shoulder 13 when the band is pushed upwardly over the pin and contract into the groove. Before the band is applied the bottom and ends of the groove are coated with cement consisting of a solution of nylon in methanol. After the band is applied, the entire surface of the pin is coated with a film of nylon applied as described in said application by repeatedly dipping the pin in a nylon-methanol solution, preferably containing a small percentage of phenol.

One of the advantages of the fabricated pin over the solid pin is that the grain of the wood is at an angle to the surface of the pin throughout its entire area. This advantage is to some extent offset by the presence of the glued seams in the impact zone of the pin. If, however, this portion of the pin is enclosed in the band, the impact of the ball cannot be centered on the glued seam and the likelihood of failure of the seams in the band pin is virtually nil.

The fabricated pin can be made cheaper than the solid pins of substantially uniform weight for the reason that the specific gravity of wood suitable otherwise for bowling pins varies substantially. Pins of the same size of the same kind of wood—seasoned hard maple—may vary several ounces in weight and the cost of selecting pieces of substantially uniform specific gravity is greater than the cost of fabricating billets of uniform weight.

The center blocks may be of a size either greater or smaller than the diameter of the neck portion of the pin and may also be made of different kinds of wood.

I claim:

1. A bowling pin consisting of a plurality of wooden blocks cemented together and wherein one of the blocks is of square cross section, extends axially of the pin from

one end to a point adjacent the mid-length of the pin and has at its inner end a cylindrical cavity symmetrical with the axis of the pin.

2. The pin of claim 1 wherein the contacting faces of the blocks lie in planes parallel with the axis of the pin.

3. The pin of claim 2 wherein the grain of the blocks forming the exposed surface of the body portion of the pin is throughout said surface at an angle to said surface not substantially more than 45°.

4. The pin of claim 2 wherein the blocks forming the surface of the body portion of the pin are four in number with the grain of the wood in each block at the middle of its circumferential dimension at substantially 90° to said surface.

5. A bowling pin consisting of wood blocks cemented together, said blocks comprising a central core of square cross section extending from end to end of the pin and symmetrical with the axis of the pin, and four blocks each having two flat faces at right angles to each other and extending axially of the pin, one of said faces being wider than the other by a distance equal to the width of said core, the wide faces of said four blocks being ce-

mented respectively to the faces of said core, with the narrow faces of the blocks co-extensive with the adjacent face of said core and cemented to the contacting face of the adjacent block.

5 6. The bowling pin of claim 5 wherein the core has an axially extending cavity near the mid length of the pin.

7. The pin of claim 5 provided with a band of molded plastic around its midportion.
